HAROLD E. DUTTON, OF LANSDOWNE, PENNSYLVANIA, ASSIGNOR TO DUTTON-NELSON, INCORPORATED, OF PHILADELPHIA, PENNSYLVANIA, A CORPORATION OF PENNSYLVANIA

SECTIONAL BOILER

Application filed January 28, 1931. Serial No. 511,666.

This invention, stated in its broadest terms, relates to heating apparatus and has more especial relation to a sectional boiler.

One object of the present invention is to provide a sectional boiler of simple construction and of high efficiency equally well adapted for steam, hot water, or vapor heating plants at a cost not exceeding conventional sectional boilers.

10 Another object of the present invention is to provide a construction in which definite separate channels are provided for the upward and downward circulation of the water in each section.

15 Another object of the present invention is to provide a construction in which each channel for the upward flow of the water is of one size and shape in cross-sectional area throughout its length, and it without branch connections or connections to other channels 20 at any point between the bottom intake opening and the top exit opening of each tube.

Still another object of the present invention is to provide a construction in which the cross-sectional area of the downward channels are substantially larger than the sum of the cross-sectional areas of all upward channels to which it connects.

Another object is to provide a construction 30 in which L-shaped tubes are employed to provide upward water channels through the combustion chamber of the boiler.

Still another object of the present invention is to provide a construction in which a baffle is arranged in parallelism with the inside wall of the section leg forming a narrow channel for upward travel of water and providing a channel of greater area for downward travel of water, said baffle at its bottom 40 being arranged slightly above the nipple connection of the boiler section but at its top terminating flush with the top of the tubes of the section.

Another object of the present invention is 45 to provide a construction of the character

stated in which the vertical tubes open directly into a steam dome of a size sufficient to efficiently permit proper steam separation and circulation of water to the downward channels.

50

Another object of the present invention is to provide a construction in which the tubes are so arranged as to provide intervening spaces between the several tubes, and between the walls of the tubes and the walls of the legs of the boiler section for the passage of combustion gases.

55

Still another object of the present invention is to provide a construction in which the tubes are so placed as to produce a staggered relation in the upward flow of the flue gases.

60

Another object of the present invention is to provide a construction in which a flue of approximately one-half the cross-sectional area of the boiler section provides for the proper exit of the flue gases.

65

Still another object of the present invention is to provide a construction in which only the water in the upward channels are brought in direct communication with the hot gases of combustion, assuring a proper direction of circulation at all times when the boiler is under normal operation.

70

Still a further object of the present invention is to provide a construction, arrangement, connection, and combination of parts for attaining the results sought by the foregoing objects.

75

The invention consists of the novel construction hereinafter described and finally claimed.

80

The nature, characteristic features and scope of the invention will be more fully understood from the following description taken in connection with the accompanying drawings forming part hereof, and in which:

85

Fig. 1 is a view in-elevation, partly in section, of a boiler embodying the invention;

90

Fig. 2 is a view in section taken upon the line 2—2 of Fig. 1;

Fig. 3 is a view in section taken upon the line 3—3 of Fig. 1; and

5 Fig. 4 is a detail view in section of one of the lower nipple connections.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 10 designates the frame of the fire box in which may be placed an oil burner, a gas burner, or a fire may be built therein for the purpose of generating heat. Mounted upon the fire box frame is the sectional boiler embodying the invention, and a description will first be given of a complete section or unit which may be made of cast-iron, brass, aluminum, or other suitable metal. A section or unit comprises a rectangular, box-like structure having a substantially L-shaped open portion upon two of its opposed vertical faces. Arranged within this open portion are a plurality of tubes, three in number, for the circulation of water. These tubes, three in number, which are designated 12, 13, and 14, are formed as an integral part of the section or unit 11. Each of these tubes is of L-shaped configuration with its lowermost or horizontal portion slightly inclined upwardly in a direction toward the vertical portion of the tube. Between each of these tubes 12, 13, and 14 there is provided a space which spaces are designated 15, 16, and 17, for the passage of combustion gases between the tubes. The reference numeral 18 designates one of the water legs with which the tubes 12, 13, and 14 communicate. The reference numeral 19 designates an oppositely disposed water leg also with which the tubes 12, 13, and 14 communicate, as they do also with the steam space or dome 30. Within this latter water leg 19 is arranged a vertically disposed baffle plate 20 which parallels the vertical inner wall of the leg and is spaced from the inner wall of the water leg to form a narrow channel 21 between the water leg 19 and the outer wall of passage 22 which is in communication with the fire box. The lower end of the baffle plate 20 is arranged in horizontal alignment with the nipple openings 23 and 24 at the bottom of the boiler section and the top of the baffle plate is arranged in a plane at the top of the tubes 12, 13, and 14. The reference numeral 25 designates a flue-way or

channel which is horizontally arranged to receive the combustion gases from the passages 15, 16, 17, and 22 from which the same pass to a flue box and thence to a chimney, not shown in the drawings. The flue-way 70 or channel 25 in cross-section is about one-half the cross-sectional area of the boiler section itself. The reference numeral 26 designates the upper nipple opening of the boiler section 11 and which is of relatively large 75 diameter. This nipple opening 26 is located well above the tops of the water tubes 12, 13, and 14 and to one side thereof in contradistinction to immediately above the same. The normal water level of the boiler sections 80 is at least three inches above the bottom of the nipple opening 26, so that plenty of steam space 30 is present above the water tubes to permit of uninterrupted agitation, thereby providing a definite, continuous circulation of water through the entire boiler and each section. As clearly shown in Fig. 3, the water tubes have staggered relation one with another so that a tortuous path is provided for the travel of combustion gases between 85 the tubes both horizontally and vertically considered. The reference numeral 27 designates the water inlet connection, and 28 designates the outlet connection. Each of the nipple openings at one end of the boiler section is closed by means of a plug 29 and a cover plate 30' may be fitted over the L-shaped space of each end of the boiler section, the same having been omitted in Fig. 1 for the purposes of better illustration. While I have shown my boiler sections as mounted upon a fire-box, obviously the boiler sections may have their bottom portions extended to form feet if desired.

What is claimed is:

1. A sectional boiler unit comprising a structure having an L-shaped opening in its side walls dividing the structure into spaced water-legs, said L-shaped opening having arranged therein water-tubes following the contour of said opening with passages between adjacent tubes for the passage of combustion gases, said water tubes being connected at their lower ends to at least one of said water legs, a horizontally arranged steam dome in a plane above said water tubes with which said water-legs and tubes communicate, and a flue-way arranged below said steam dome and communicating with the tops of said combustion gas passages. 105
2. A sectional boiler unit comprising a structure having an L-shaped opening in its side walls dividing the structure into spaced water-legs, said L-shaped opening having arranged therein water-tubes including ingress and egress openings said tubes following the contour of said opening with passages between adjacent tubes for the passage of combustion gases, said water tubes being connected at their lower ends to at least one of 115
3. A sectional boiler unit comprising a structure having an L-shaped opening in its side walls dividing the structure into spaced water-legs, said L-shaped opening having arranged therein water-tubes following the contour of said opening with passages between adjacent tubes for the passage of combustion gases, said water tubes being connected at their lower ends to at least one of 120
4. A sectional boiler unit comprising a structure having an L-shaped opening in its side walls dividing the structure into spaced water-legs, said L-shaped opening having arranged therein water-tubes following the contour of said opening with passages between adjacent tubes for the passage of combustion gases, said water tubes being connected at their lower ends to at least one of 125
5. A sectional boiler unit comprising a structure having an L-shaped opening in its side walls dividing the structure into spaced water-legs, said L-shaped opening having arranged therein water-tubes following the contour of said opening with passages between adjacent tubes for the passage of combustion gases, said water tubes being connected at their lower ends to at least one of 130

5 said water legs, a horizontally arranged steam dome in a plane above said water tubes with which said water-legs and tubes communicate, a flue-way arranged below said steam dome and communicating with the tops of said combustion gas passages, and a steam outlet connection for said steam dome arranged in alignment with the ingress openings of the water-tubes which ingress 10 openings are arranged at the bottom of said L-shaped portion but out of alignment with the water-tube egress openings.

15 3. A sectional boiler unit comprising a structure having an L-shaped opening in its side walls dividing the structure into spaced water-legs, said L-shaped opening having arranged therein water-tubes including vertically disposed portions following the contour of said opening with passages between 20 adjacent tubes for the passage of combustion gases, said water tubes being connected at their lower ends to at least one of said water legs, a baffle plate in one of said water-legs arranged in parallelism with the vertical 25 portions of said water-tubes and combustion gas passages, a horizontally arranged steam dome in a plane above said water-tubes with which said water-legs and tubes communicate, and a flue-way arranged below 30 said steam dome and communicating with the tops of said combustion gas passages.

35 4. A sectional boiler unit comprising a structure having an L-shaped opening in its side walls dividing the structure into spaced water-legs, said L-shaped opening having arranged therein water-tubes following the contour of said opening with passages between adjacent tubes for the passage of combustion gases, said water tubes being connected 40 at their lower ends to at least one of said water legs, the cross-sectional area of each water-tube being of the same dimension throughout its extent, a horizontally arranged steam dome in a plane above said water-tubes with which said water-legs and tubes communicate, and a flue-way arranged below 45 said steam dome and communicating with the tops of said combustion gas passages.

50 5. A sectional boiler unit comprising a structure having an L-shaped opening in its side walls dividing the structure into spaced water-legs, said L-shaped opening having arranged therein water-tubes following the 55 contour of said opening with passages between adjacent tubes for the passage of combustion gases, said water tubes being connected at their lower ends to at least one of said water legs, a horizontally arranged steam dome in a plane above said water-tubes with which said water-legs and tubes communicate, and a flue-way arranged below said steam dome and communicating with the tops of said combustion gas passages.

60 6. A sectional boiler unit comprising a

structure having an L-shaped opening in its side walls dividing the structure into spaced water-legs, said L-shaped opening having arranged therein water-tubes following the contour of said opening with passages between 70 adjacent tubes for the passage of combustion gases, said water tubes being connected at their lower ends to at least one of the water legs, said water-tubes being arranged in staggered relation, a horizontally arranged steam dome in a plane above said water-tubes with which said water-legs and tubes communicate, and a flue-way arranged below said steam dome and communicating with the 75 tops of said combustion gas passages.

80 7. A sectional boiler unit comprising a structure having an L-shaped opening in its side walls dividing the structure into spaced water-legs, said L-shaped opening having arranged therein water-tubes including horizontal and vertically disposed portions, said tubes following the contour of said opening with passages between adjacent tubes for the passage of combustion gases, said water tubes being connected 85 at their lower ends to at least one of said water-legs, the horizontal portions of said water-tubes being slightly inclined in a direction toward the vertical portions thereof and arranged in parallelism, a horizontally arranged steam dome in a 90 plane above said water-tubes with which said water-legs and tubes communicate, and a flue-way arranged below said steam dome and communicating with the tops of said combustion 95 gas passages.

100 8. A sectional boiler unit comprising a structure having an L-shaped opening in its side walls dividing the structure into spaced water-legs, said L-shaped opening having arranged therein water-tubes following the contour of said opening with passages between adjacent tubes for the passage of combustion gases, said water tubes being connected at their lower ends to at least one of said water legs, a horizontally arranged steam dome in a plane above said water-tubes with which said water-legs and tubes communicate, a flue-way arranged below said steam dome and communicating with the tops of said combustion 105 gas passages, and a cover plate 110 removably fitted to said L-shaped opening.

115 9. A sectional boiler unit comprising a structure having an L-shaped opening in its side walls dividing the structure into spaced water-legs, said L-shaped opening having arranged therein water-tubes including ingress and egress openings, said tubes following the contour of said opening with passages between adjacent tubes for the passage of combustion gases, said water tubes being connected at their lower ends to at least one of said water legs, a horizontally arranged steam dome in a plane above said water-tubes, with which said water-legs and tubes communicate, a flue-way arranged below said 120 125 130

steam dome and communicating with the tops of said combustion gas passages, a steam outlet connection for said structure arranged in alignment with the ingress openings of the water-tubes, which ingress openings are arranged at the bottom of said L-shaped portion, but out of alignment with the water-tube egress openings, and an upper nipple connection for the boiler section of relatively large diameter, the bottom wall of which is arranged in a plane appreciably below the normal water-line of the boiler section.
